UNITED STATES PATENT OFFICE.

AUGUST C. HANSCH, OF JERSEY CITY, NEW JERSEY.

APPARATUS FOR TREATING PHOTOGRAPHIC PLATES.

1,135,111.

Specification of Letters Patent. Patented Apr. 13, 1915.

Application filed January 10, 1914. Serial No. 811,288.

To all whom it may concern:

Be it known that I, AUGUST C. HANSCH, a citizen of the United States, and a resident of Jersey City, in the county of Hudson and State of New Jersey, have invented certain new and useful Improvements in Apparatus for Treating Photographic Plates, of which the following is a specification.

This invention relates to apparatus for 10 treating photographic plates.

The invention is specifically applicable for developing and finishing photographic process plates.

The organization of the invention comprises a tank with a plurality of compartments for liquids, and means for moving a plate pack with plates to be treated from the liquid in one compartment to the liquid in another compartment. In addition to the 20 above and to expedite the action of the liquids on the plates, I may add means to agitate the liquids in the compartments.

With this invention the various steps in treating a photographic plate are automatically and consecutively accomplished, permitting the operator using the invention to employ the intervals of time used in treating the plates, for other useful purposes.

Figure 1 shows a top plan view of one 30 form of the invention with a portion broken away, Fig. 2 represents an elevation of the invention with a partial section as on the line 2, 2, of Fig. 1, Fig. 3 shows a front elevation of a detail, Fig. 4 is an enlarged view 35 of a portion of Fig. 2 with a detail in axial section, Fig. 5 shows a top plan view of Fig. 4, Fig. 6 is a partial section of Fig. 4 on the line 6, 6, Figs. 7, 8, 9 show top plan views of details, Fig. 10 represents a fragmentary 40 top plan view of a modification of the invention and Fig. 11 represents an elevation of the modification with a partial section as on the line 11, 11 of Fig. 10.

Referring to Figs. 1 to 9 inclusive, the invention is shown to comprise an annular tank having in this instance the main compartments designated by the numerals 20 to 31 inclusive. Each compartment is shown with a secondary horizontal compartment 40 from which extends a vertical leg 41. Perforations 42 are made in the bottom of each of the main compartments and constitute miniature ducts between each main compartment and its secondary compartment. In 55 the axial center of the tank is located driven shaft 46 which is designated as the second

shaft, and which near its upper end has fastened thereto a double sleeve with the outer cylindrical wall 47, inner cylindrical wall 48, that are connected by the top walls 49, 50 and the secondary sleeve 51. A bottom wall 52 with the secondary sleeve 53 extends from the wall 48. The sleeves 51 and 53 are fastened to the said shaft 46 by means of the pins 54. A pair of air outlet openings 59 and 60 are made in wall 47. Concentric with and surrounding the wall 47 is shown an outer sleeve with the cylindrical wall 61 having outlets 62 for the conduits 63 that extend to the vertical legs 41 of the compartments 40. The wall 61 has connected thereto the bottom wall 64 which has an axial opening for the shaft 46. A cover 65 is supported on the wall 61 and has an axial opening for the shaft 46. An air inlet opening 70 is 75 formed in the bottom wall 64 for the air inlet pipe 71. At the outer lower edge of the tank is indicated a supporting ring 72 which is carried on the legs 73. A bed plate 76 has supported thereon a frame, with the legs 77 that have formed therewith the D shaped top member 78. In the member 78 are formed the bearings 80, 81, 82, 83, 84 and 85. The bed plate 76 supports the step bearings 80, 91, 92, 93, 94 and 95 and the journal bearing 96. The D shaped member 78 has formed therewith the journal bearings 100, 101, with removal caps 102. A worm shaft 103 with the worm 104 is supported in the bearings 100, 101. Means not shown are provided to turn said worm shaft 103. A driving shaft 110 is journaled in the bearings 80 and 90, and it has fastened thereto the worm wheel 111 that meshes with the worm 104. Gears 112, 113 of the same pitch diameter are fastened to the shaft 110, which latter also has fastened thereto the gear 114 slightly smaller in pitch diameter than said gears 112, 113. A main shaft 118 with three collars 119 fastened thereto is journaled in the bearings 81 and 91. It carries the spur gears 120, 121, 122, all of the same pitch diameter and which are respectively on the same levels as the gears 112, 113 and 114. A shaft 124 is journaled in the bearings 85 and 95, and which 100 slidably carries the sleeve 125 having the handle 126. A screw 127 in threaded engagement with said sleeve 125 enables the latter to be clamped in different positions on the shaft 124 by the end of said screw engaging small cavities 128 in the shaft 124. An 105 arm 129 with a slot 130 extends from the sleeve

125. A stud 131 is adjustably clamped to the arm 129, by means of a nut 132 which engages a threaded end 133. The said threaded end 133 extends through the slot 130. An intermediate gear 134 is journaled on the stud 131, and by means of the appurtenances just described can be made to mesh respectively with the gears 112, 120, or the gears 113, 121, or the gears 114, 122. The shaft 118 carries what I will term a triplex spur gear 135 which is fastened to the gear 120 by bolts 135^a. It has a circumferential dove-tailed groove 136, a dove-tailed groove 137 in its top face and a groove similar to the latter in its bottom face. It has the detachable portions 137^a in the top and bottom faces and the detachable portion 136^a in its circumference. In this instance the said grooves have fastened therein teeth as follows: In the circumferential groove 136 are fastened the detachable pairs of teeth 138, 139, 140, 141, 142 and the group of teeth 143. In the groove 137 are fastened the detachable teeth 144, 145, 146, 147, 148 and 149 which are each respectively located at one side of the pairs of teeth 138, 139, 140, 141, 142 and the group 143. In the groove of the bottom face of the wheel 135 are fastened the detachable teeth 150, 151, 152, 153, 154 and 155 which are each respectively located at the other side of said pairs of teeth and group. A triplex spur gear 156 similar in construction to the gear 135 is carried on the shaft 118, and is bolted to the gear 121 by the bolts 156^a. It has a circumferential groove 157 similar to 136, and a groove 158 similar to 137 and a groove in its bottom face similar to the corresponding groove in the wheel 135. In the circumferential groove 157 are fastened the detachable pairs of teeth 160, 161, 162, 163, 164, 165, 166, 167, 168 and the group 169. In the groove 158 are fastened the detachable teeth 170, 171, 172, 173, 174, 175, 176, 177, 178, 179 which are relatively a little to one side of the pairs of teeth 160 to 168 and the group 169. In the groove of the bottom face of the gear 156 are detachably fastened the teeth 180, 181, 182, 183, 184, 185, 186, 187, 188 and 189 which are each relatively located on the other side of the pairs of teeth 160 to 168 and the group 169. The gear 156 has portions 158^a similar to 137^a and 157^a similar to 136^a. The shaft 118 carries what I term a quadruple gear 195 which is fastened to the gear 122 by the bolts 195^a. It has the dove-tailed circumferential grooves 196, 197 one over the other, the dove-tailed groove, 198 in its top face and a similar dove-tailed groove in its bottom face. In the top circumferential groove 196 are fastened the detachable pairs of teeth 200 to 211 inclusive and the group of teeth 212. In the groove 198 are fastened the detachable teeth 214 to 226 inclusive to one side of the pairs of teeth 200 to 211 and group 212. The gear 195 has portions 198^a similar to 137^a and portions 196^a and 197^a similar to 136^a. In the groove of the lower face of the gear 195 are fastened the detachable teeth 228 to 240 which are located at the other sides of the pairs of teeth 200 to 211 and the group 212. In the lower circumferential groove 197 is fastened the group of teeth 241. In the groove 198 is fastened a tooth 242 to one side of the group 241 and in the groove in the bottom of the wheel 195 is fastened the detachable tooth 243 at the other side of the group 241. On the shaft 46 are fastened the gears 250, 251, 252, and 253. The gear 250 meshes with the pairs of teeth 138 to 142 and the group of teeth 143, on the gear 135. The gear 251 meshes with the pairs of teeth 160 to 168 and the group of teeth 169 on the gear 156. The gear 252 meshes with the upper pairs of teeth 200 to 211 and the group of teeth 212 on the gear 195. A second spindle 259 is supported in the journal bracket 96 and has fastened thereto a gear 260, which meshes with the gear 253, and the group of teeth 241 in the gear 195. A third shaft 264 is journaled in the bearings 83, 93 and has fastened thereto the gears 265, 266, 267, 268, 269 and 270. A fourth shaft 274 is journaled in the bearings 84, 94 and has fastened thereto the gears 275, 276 and 277. The gear 265 meshes with the teeth 144 to 149 on the gear 135. The gear 266 meshes with the gear 275 and then meshes with the teeth 150 to 155 on the gear 135. The gear 267 meshes with the teeth 170 to 179 on the gear 156. The gear 268 meshes with the gear 276 which latter meshes with the teeth 180 to 189 on the gear 156. The gear 269 meshes with the teeth 214 to 226 and the tooth 242 on the gear 195. The gear 270 meshes with the gear 277 and the latter meshes with the teeth 228 to 240 and the tooth 243 of the gear 195. On the shaft 46 is fastened a sleeve 282 which supports a double gear comprising the spur gear 283 and the bevel gear 284. The shaft 264 has fastened thereto the gear 285 which meshes with the gear 283. The shaft 46 has fastened thereto a journal bearing 286 for the horizontal spindle 288 which carries at one end the gear 289 and at the other end the bevel pinion 290 that meshes with the bevel gear 284. The shaft 46 has an opening for the spindle 288. At the upper end of the shaft 46 is fastened an arm 291 which latter has formed therewith the vertical bearings 292, 293 and the horizontal bearing 294. The bearing 294 supports one end of the spindle 288, and in the bearings 292 and 293 is guided a rack shaft 295 with the rack teeth 296 and an offset 297 at its lower end. The teeth 296 mesh with the gear 289. At the lower end of the offset 297 is fastened a collar 300 of a plate rack. Rear diverging members 301, and the forward double di-

verging members 302 have their upper ends fastened to said collar 300. Horizontal shelves 304 are supported on the members 301 and 302.

To use the invention solutions as follows: that is to say, developer, water, cyanid, water, copper, water, silver, water, iodid, water, mercury and water may be respectively poured in the compartments numbered 20 to 31. The solutions gravitate to the secondary horizontal compartments 40 through the perforations 42. Air supplied by the pipe 71 enters the double sleeve having the walls 47 and 48 and from the latter it enters the conduits 63 through the openings 59 and 60 during the rotations of the double sleeve. One of the conduits 63 receives its charge of air before it is shut off on the one previously charged. The air forces the solutions through the perforations 42 into the compartments 20 to 31 and causes the solutions to act on plates carried by the plate racks.

The worm shaft 103 is turned by power not shown, and which through the worm 104 and worm wheel 111 turns the shaft 110. The sleeve 125 may be considered positioned so that rotation is transmitted from gear 113 to the gear 134 and then to gear 121. The sleeve 125 can be positioned so that rotation is transmitted to either the gear 120 or the gear 122. The gear 121 carries with it the triplex spur gear 156. The pairs of teeth 160 to 168 and also the group of teeth 169 intermittently rotate the gear 251. The said pairs of teeth rotate the gear 251 so that the arm 291 is carried in the direction of the arrow B to proper positions over the compartments 20 to 31, that is to say the arm is carried from over one compartment to the other as required, and the group of teeth 169 carry the said arm 291 over a number of said compartments, depending upon the number of teeth in the group. Just before the arm 291 begins to swing one of the teeth 170 to 179 engages the gear 267. The gear 267 turns the shaft 264 and then through the gears 285, 283, 284 and 290 the spindle 288 is rotated. With the spindle 288 the gear 289 is turned which latter raises the rack shaft 295, to raise the plate rack attached thereto so that it can clear the walls of the compartments 20 to 31 while the arm 291 swings. At the proper time the teeth 180 to 189 mesh with the gear 276, which turns the gear 268. The latter gear reverses the rotations of the shaft 264 and consequently the rack shaft 295 is lowered by means of the gearing interposed between said rack shaft and the shaft 264. The spaces between the pairs of teeth 160 to 168 and the group 169 allows the plate-rack to remain in the various compartments for the requisite length of time. When the gear 134 allows rotation to be transmitted from the

gear 112 to the gear 120 similar intermittent motions are given to the shafts 46 and 264, depending upon the distribution of the teeth on the gear 135. When the gear 134 meshes with the gears 114 and 122 the quadruple gear 195 is turned. When the latter gear turns the shafts 46 and 264, they are turned in a manner similar to that described, depending upon the distribution of the pairs of teeth 200 to 211 and the group 212, the teeth 214 to 226, and the teeth 228 to 240. The group of teeth 241 in the second circumferential groove 197 reverse the rotations of the shaft 46 and consequently swing the arm in a direction opposite to the arrow B. Consequently when the gear 114 is performing its functions the arm 291 turns in one direction while raising and lowering the plate-rack and also turns in the opposite direction and raises and lowers the plate-rack.

In the modification of the invention shown in Figs. 10 and 11 the tank with the compartments 20 to 31 is rotated instead of remaining stationary and the arm 291 remains stationary instead of turning. In this modification the bed plate 76 supports a frame with the same legs 77 as already described with the exception that the D shaped member 78 has formed therewith an extension 310. The said frame carries the shaft 46 with the gears 250 to 253 as already described, the shaft 110 with the worm wheel 111, gears 112 to 114 as described, the shaft 116 with the gears 120, 135, 121, 156, 122, 195 as described, the shaft 124 with its sleeve 125 as described, the shaft 264 with its gears 265 to 270 as described. The shaft 264 has also fastened thereto the gear 285. The shaft 274 carries the gears 275 to 277 as described, and the spindle 259 has fastened thereto the gear 260 as described. The frame with the D shaped member 78 in this modification has journaled therein the shaft 315 with the gears 316 and 317 fastened thereto. The gear 316 meshes with a gear 320 fastened to the shaft 46. A shaft 325 is journaled in the said frame and has fastened thereto the gear 326 which meshes with a gear 317. A gear 327 is fastened to the upper end of the shaft 325 and meshes with the internal gear 328 fastened to the outer annular wall of the leg 41 of the tank having the compartments 20 to 31. The tank in this modification revolves on the ring 72. The said ring is supported on legs 73 as already described. The shaft 46 is encircled by the sleeve 335 to which is fastened the bevel gear 336 similar to 284 and the gear 283. Within the sleeve 335 is located the stationary shaft 337 which is fastened to a fitting 338 secured to a ceiling or other support not shown. The shaft 337 carries the journal bearing 286 for the spindle 288 having fastened thereto the bevel pinion 290.

and gear 289. The arm 291 carries the rack-shaft 295 which meshes with the gear 289 and carries the collar 300 with the plate rack as described. In the axial center of 5 the tank with the compartments 20 to 31 is shown a double sleeve 341 which is fastened to the frame having the D shaped member 78 by means of dowel pins 342. It has two openings 343, 344 similar to 59 and 10 60. An outer sleeve 345 surrounds the sleeve 341 which has outlets for the conduits 63 that connect with the legs 41 as already described. The air inlet pipe 71 is connected to the bottom 341^a of the double 15 sleeve 341. To operate this modification the plates are placed on the plate racks in the compartments 20 to 31 as already described. Rotation is transmitted from the worm shaft 103 to shaft 46 and 264 as described. The shaft 264 turns the gear 285^a which meshing with the gear 283^a turns the sleeve 335. Thereby the bevel gear 336 turns the bevel pinion 290, and the latter turns the spindle 288 as before, by virtue of which 25 the plate rack is raised and lowered at the proper times, the arm 291 remaining stationary. With the rotations of the shaft 46 the gear 320 turns the gear 316, and the latter through the gears 317, 326 and 327 rotates the internal gear 328 carried on the 30 tank having the compartments 20 to 31. The tank makes the same number of revolutions as the shaft 46, and while it turns air is transmitted from the double sleeve 341 through the conduits 63 to the legs 41 as 35 already described.

Having described my invention what I desire to secure by Letters Patent and claim is:

- 40 1. In an apparatus of the character described the combination of a tank having a plurality of compartments for liquids, and means to force air through the liquids in said compartments consecutively one after 45 the other.
2. The combination of a plate rack, means to swing said rack in one direction, other means to swing said rack in a reverse direction and means to move the plate rack in a 50 plane perpendicular to which it swings.
3. In an apparatus of the character described the combination of a tank having a plurality of compartments, means to force air through the liquid of one of said compartments during a predetermined interval of time and means to begin forcing air through the liquid of a second compartment before the termination of forcing the air through the liquid of the first compartment. 55
- 60 4. In an apparatus of the character described the combination of a tank having a plurality of compartments, a movable plate rack for said compartments, means to raise or lower the plate rack into or out of any of 65 the compartments, means to move the said

plate rack in one direction from one compartment to another and means to move the plate rack in an opposite direction.

5. In an apparatus of the character described the combination of a tank having a 70 plurality of compartments for liquids, a movable plate rack for said compartments, means to raise or lower the plate rack into or out of any of said compartments, said means being adjustable to vary the time of immersion of said rack in said liquids and means to move the plate rack when raised or being raised to a second compartment to be lowered into the latter. 75

6. In an apparatus of the character described the combination of a tank having a plurality of compartments for solutions, a plate rack, means to raise or lower the plate rack into or out of said compartments, said means being adjustable to vary intervals of 80 time of immersion of said rack in said solutions. 85

7. In an apparatus of the character described the combination of a tank having a plurality of compartments, a main shaft for 90 the tank, means to turn the shaft, a gear on the main shaft, a second and a third shaft adjacent to the main shaft, a gear on the main shaft with teeth intermittently located thereon, a gear on the second shaft meshing 95 with the said teeth on the main shaft to intermittently rotate the second shaft, an arm on the second shaft, a plate rack slidably connected to said arm, a gear on the third shaft, teeth intermittently locked on the 100 main gear meshing with teeth of the gear on the third shaft, a spindle carried in the arm and means interposed between the third shaft and spindle to turn the latter, a fourth shaft, a gear on the fourth shaft meshing 105 with the gear on the third shaft, teeth intermittently located on the main gear meshing with the gear on the fourth shaft to reverse the rotations of said spindle. 110

8. In an apparatus of the character described the combination of a tank having a plurality of compartments, a main shaft for the tank, means to turn the main shaft, a gear on the main shaft, teeth intermittently and detachably fastened to the circumferential surface of the gear and teeth intermittently and detachably fastened to the top face and to the bottom face of the gear, a second shaft adjacent to the main shaft, a gear on the second shaft meshing with teeth 115 on the said circumferential surface, an arm connected to the second shaft, a plate rack slidably supported on said arm, a third shaft, a gear on the latter shaft meshing 120 with the teeth on one of the surfaces of the main gear, a spindle carried on the arm and connections between said spindle and the plate rack and connections between the spindle and the gear on the third shaft, a fourth shaft and a gear on the fourth shaft mesh- 125 130

ing with the teeth on the other face of the first gear and also meshing with the gear on the third shaft.

9. In an apparatus of the character described the combination of a tank having a plurality of compartments, a main shaft for the tank, means to turn the shaft, a gear on the shaft having a groove in its top face and bottom face and having a pair of grooves on its circumferential surface, teeth adjustably fastened in each of said grooves, a second shaft adjacent to the main shaft, a gear on the second shaft meshing with the teeth in one of the circumferential grooves, a spindle journaled adjacent to the second shaft, a gear on the spindle meshing with the teeth in the second circumferential groove and the teeth on the second shaft, an arm carried on the second shaft, a plate rack slidably connected to said arm, a third shaft adjacent to the first shaft, a gear on the third shaft meshing with the teeth in the groove of the top face of the first gear, a fourth shaft adjacent to the main shaft, a gear on the fourth shaft meshing with the teeth in the groove of the other face of the main gear, a second gear on the third shaft meshing with the gear on the fourth shaft, a horizontal spindle on the arm, connections between the latter spindle and the third shaft and connections between the latter spindle and the plate rack.

10. In an apparatus of the character described the combination of a tank having a plurality of compartments, a driving shaft for the tank, means to turn the shaft, a plurality of gears one over the other on the shaft, a main shaft journaled adjacent to the driving shaft, a plurality of gears one over the other rotatably supported on the main shaft and respectively on the same levels with the gears on the driving shaft, an intermediate gear adjustably supported adjacent to the driving shaft and means to mesh said intermediate gear with any gear on the driving shaft and its accompanying gear on the main shaft, a gear with teeth on its circumferential surface and on its top and bottom faces connected to each gear on the main shaft, a second shaft adjacent to the main shaft, gearing on the second shaft meshing with the teeth on the said circumferential surface, an arm carried on the second shaft, plate rack slidably connected to said arm for said compartments, a third shaft adjacent to the main shaft, gears on the third shaft meshing with the teeth on one of the faces of the gears on the main shaft, a fourth shaft, gears on the fourth shaft meshing with teeth on the other faces of the gears on the main shaft, a spindle carried on the arm, gearing interposed between said spindle and the third shaft, and gearing interposed between the spindle and the plate rack.

11. In an apparatus of the character de-

scribed the combination of an annular tank, main compartments for the tank having perforations in the bottom walls thereof, a secondary compartment with a leg for each main compartment, a double sleeve having 70 an outer wall and inner wall with its axis coincident with the axis of the tank, a pair of openings in said outer wall, an outer stationary sleeve surrounding the double sleeve, conduits connecting openings in the outer 75 sleeve with openings in the legs of the secondary compartments, the openings in the outer sleeve enabled to register with the openings in the double sleeve, a rotary shaft connected with the double sleeve, an arm fastened to the shaft, a plate rack slidably connected to the arm, a spindle carried on the arm, means to rotate the spindle in two directions, connections between the spindle and plate rack, and means to conduct air to 80 85 the double sleeve.

12. In a tank having a plurality of compartments for liquids to treat a plate, means to force air through the liquid in any compartment for a predetermined length of 90 time.

13. In an apparatus of the character described the combination of a tank having a plurality of compartments, a movable plate rack for said compartments, adjustable 95 means to raise said plate rack relatively to any of said compartments, adjustable means to swing said plate rack from over one of said compartments to over another and adjustable means to lower said plate-rack into 100 the latter compartment.

14. The combination of a plate rack, means to swing said rack in one direction for a predetermined distance, and other means to swing said rack in a reverse direction 105 for a predetermined distance.

15. The combination of a plate rack, means to swing said rack in one direction for a predetermined distance, other means to swing said rack in a reverse direction for a 110 predetermined distance and means to raise and lower the plate rack, the latter means being adjustable to maintain the rack at its upper or lower level a predetermined interval of time.

16. In an apparatus of the character described the combination of a tank having a plurality of compartments for liquids, a plate rack for the apparatus and means to remove the plate rack from any compartment and 120 lower it into any other of said compartments.

17. In an apparatus of the character described the combination of a tank having a plurality of compartments for solutions, a 125 plate rack for the apparatus, means to move the plate rack from one compartment to another and means to maintain said plate rack in the solution of any of said compartments for a predetermined length of time. 130

- 6
18. In an apparatus of the character described the combination of a tank having a plurality of compartments for fluids, means to force air through the fluid of one of said compartments, and means to force air through the fluids of one of the other compartments not adjacent to first.
19. In an apparatus of the character described the combination of a tank having a plurality of compartments for fluids, a movable plate rack for said compartments, means

to raise and lower the plate rack into or out of any of said compartments, and means to move said plate rack into and out of any combination of said compartments.

Signed in the borough of Manhattan in the county of New York and State of New York this 9th day of January, A. D. 1914.
